COPYHOLDER WITH COMPARTMENT FOR COPIED SHEETS

Louis G. Harlam, North Hollywood, Calif.

Application February 4, 1952, Serial No. 269,845

6 Claims. (Cl. 120—32)

1

This invention relates to a typist's copy holder with a basal portion which combines the functions of forming a support for a typewriter and of providing a space containing a compartment to receive in pack formation the used sheets of the copy.

Although numerous copy holding devices have been devised, there is a felt need, in the art to which this invention pertains, for the provision of a copy holding device which will, in a space economizing manner, provide for the temporary storing of a considerable number of the sheets which have been copied, so that they will be out of the typist's way and yet in a readily accessible situation.

Accordingly, one of the objects of the present invention is to provide a copy holding device to fill satisfactorily the above noted need.

In regard to the above mentioned space economizing feature, a more specific object of the invention is to provide a copyholder which will utilize space under the typewriter (or other analogous key operable machine which the operator is using), to contain a drawer into which the used copy sheets will be mechanically delivered as fast as the matter inscribed on them is copied.

Other objects, advantages and features of invention will hereinafter appear.

Referring to the accompanying drawings, which illustrate a preferred embodiment of the invention, now reduced to practice,

Fig. 1 is a perspective view of the complete device, viewing it in front.

Fig. 2 is a longitudinal midsection, the position of a typewriter supported on the device being delineated in phantom lines.

Fig. 3 is a cross section on line 3—3 of Fig. 2.

Fig. 4 is a fragmentary perspective view looking at the front part of the basal portion of the device, the slide for supporting the copied sheets being shown in an extended position.

Referring in detail to the drawings, the copy holding device therein shown which may have its various wall portions made of a plastic substance, such as "Lucite," comprises a hollow base portion 7 which forms a receptacle substantially rectangular as viewed either in plan or cross section, and which is supportable on a desk or table. This base has a top wall 8 which, when the device is supported as aforesaid, extends horizontally and forms a suitable support for the typewriter 9 delineated in phantom lines in Fig. 2.

A hollow, chute forming standard 10 upstands from and interiorly communicates with the rear

5 part of the hollow base 7, said base having twin side walls 11, each with an upward extension 12, said wall extensions 12 forming the side walls of said standard 10.

10 The forwardly concave front plate or wall 13 of the standard 10 has side edge portions which overlie the front edge portions of the side walls 12 of said standard. The lower edge portion of said wall 13 rests upon the upper edges of the side walls 11 of the used copy compartment and abuts against the rear end of the horizontal wall or plate 8, the latter wall preferably having its rear edge beveled as shown in Fig. 1 to aid in keeping said front plate 13 in place. The upper edge portion of said plate 13, each side thereof, fits within a notch 13a (see Fig. 2) provided for it under a forwardly projecting shoulder 13b.

15 The rear edge portion of each side wall 12 of the hollow standard 10 is arcuate, the amount of curvature in each edge being greatest throughout the upper portion of the standard. Said edges are each bordered by a parallel, adjacent groove 17 and the side edge portions of the rear wall 14 of the chute are in a contained, secured relation to the grooves provided, as aforesaid.

20 The aforesaid base portion 7 of the device has a substantial floor 20 and in a spaced relation to the rear end of said floor there upstands a partition plate 21 which partitions the interior of said base off from an alcove 22 partly closed in at its rear side by an upstanding wall portion 23, said alcove spanning the space between the rear lower corner portions of the aforesaid side walls 11 of the hollow base 7. The lower edge 25 of the aforesaid wall 14, and the lower ends of the containing grooves therefor, terminate on a level with the top of said upstanding wall 21, thus forming a structure which guides each descending sheet 16 onto the top of the pack of such sheets accumulating within the hollow base 7.

25 Near the bottom of each side of the hollow base 7 is a horizontal, inwardly projecting rib 25, and as a result of the presence of these ribs an underlying guide groove 26 is produced along each side of the floor of the base 7 to receive a drawer means shown as a slide 27 having a closure 28 hinged to its front end by a pair of hinges 29. This swingable closure is provided with an operating knob 30 secured thereto by fastening means 31, said knob being usable not only to swing said closure but also to extend and retract said slide. In Figs. 1 and 4 a rectangular countersink 28a is shown provided in the front edge portion of each side wall 11 of the

base 7, into which said closure is slidable after it has been swung upwardly.

Returning to the copy holding and feed means, having the general designation 15 in Figs. 1 and 2, said means comprises a conventional platen roller 35 and its appurtenances, which include the milled knob 36, line advancing lever 37 and bail carried pair of small guide rollers 38. The upper end portions of the side walls 12 of the chute forming standard 10 carry suitable bearing plates 39 for said platen, said plates being secured internally to said walls by screws 40, as illustrated in Fig. 2. Said plates also carry between them a front guide roller 41 for the up-fed copy carrying sheet 16.

The side walls 12 of the standard 10 are sufficiently thick, at least throughout their upper end portions, to afford anchorage for a pair of screws 45 whereby a rectangular, opaque, line guide screen 46 is attached subjacent to the platen 35 in a vertically-adjustable manner; said screen having near its ends transverse slots 47 which loosely contain the outer end portions of the shanks of said screws 45. By this means said screen may be vertically adjusted to accommodate the line of vision of typists of different stature, and also so as to bring each successive line to be copied just above the upper edge of said screen after each line advancing operation of the sheet being copied by means of the aforesaid lever 37.

Said screen 46 has a downwardly directed upper portion 48 which forms a rearwardly extending guide lip that aids in directing the sheets to be copied from into their operative position between the platen 35 and guide roller 41.

The knob-equipped swingable closure 28 carried by the front end of the slide 27 is usable more or less to withdraw the slide 27 from the hollow base 7, withdrawing said slide to the extent shown in Fig. 4 rendering convenient access to the front end of the pack of copied sheets for their manual removal from the compartment in which they are contained. Also said closure is upswingable, when the slide is partially retracted, to a position wherein it can be slid into fully retracted position wherein it forms a closure for the door opening 1a at the front end of the base 7.

The aforesaid opposed grooves in the side walls 12 of the casing are open at their upper ends so that, as the final step in assembling the parts of the device, the copy guide plate 14 can be fed downwardly into them.

The operation of the device will for the most part be readily understood from the foregoing description. The lever 37 is so arranged as to operate like the line spacing lever of a typewriter, being settable to advance the mounted copy sheet upwardly one, two or three line spaces each time it is operated.

It will be observed that the lower edge portion of the arcuate, sheet guiding plate 14 is forwardly directed at an inclination considerably nearer horizontal than vertical, and that said lower edge portion is located at a somewhat higher level than the top wall 8 of the boxed in front part of the device and, consequently, also at a higher level than the upper surface of the horizontal pack of sheets in the boxed in part when the latter approaches capacity filling. Hence it is evident that, so long as there is room for adding more sheets to the pack, the arcuate plate will positively direct additional sheets thereonto. Furthermore, edgewise displacement of the descending sheets cannot occur because the arcuate

plate is closely contained, throughout its entire length, between the upstanding side wall extensions 12. The upper edge portion of the upstanding basal plate 21 engages along the lower edge portion of the arcuate, plastic plate 16, stabilizing the latter against bowing from the horizontal along its lower edge, thus insuring that the descending copied sheets are not bowed in a manner that would interfere with their proper delivery to the pack of used sheets.

Although the device has been described as usable in conjunction with a typewriter, it is to be understood that various other typographical machines may be supported upon the basal portion thereof and the copy sheets used in their operation can be handled by the device in the same manner as the typist's copy, already described.

I claim:

20. 1. In a copy holder, a hollow base supportable upon a desk or table and having when so supported a front portion with a top surface which extends horizontally and forms a typewriter support, a hollow standard upstanding from the rear portion of said base and interiorly communicating therewith thus forming a copy chute, copy holding means carried by the upper part of said standard and manually operable in a step-by-step fashion to feed the copy downwardly from said standard into the aforesaid front portion of said hollow base, and a drawer means normally occupying said front portion of said hollow base in an underlying relation to the typewriter when on said support to receive copy fed therewith from said copy holding means, said base having a front end portion through which said drawer means is manually extensible to afford access to used copy contained therein.

2. The structure set forth in claim 1 and said drawer means comprising a substantially rectangular floor and a door opening at its front end, a slide overlying said floor, said slide being positioned to receive the copied sheets entering said base as aforesaid, and means carried by an end portion of said slide usable partly to withdraw said slide through said door opening.

3. The subject matter of claim 2 and said slide carried means being a swingable member which forms a closure for said door opening when the slide is in its retracted position.

4. In a copyholder and copychute usable in conjunction with typographical machines, a hollow base supportable upon a desk or table and having when so supported a boxed in front portion to contain copied sheets which is substantially rectangular as viewed in plan, said front portion having a top surface which extends horizontally and forms a support for a typographical machine, a hollow standard upstanding from the rear portion of said base and interiorly communicating therewith thus forming a copychute, said copychute having a rear wall which comprises an arcuate upwardly and downwardly extending sheet guiding plate with its concave side directed forwardly, said plate having a lower edge portion which extends downwardly at an inclination nearer horizontal than vertical and which is positioned at a slightly higher level than the upper surface of the pack of copied sheets in the aforesaid boxed in portion when the latter is filled to capacity, and a drawer means occupying said boxed in front portion of said hollow base to receive the sheets from said copychute, said boxed in portion having a front end through which said drawer means is manually extensible

to afford access to used copy contained therein.

5. The subject matter of claim 4 and said hollow standard having side walls which border said arcuate plate throughout its length, thus preventing edgewise displacement of the descending copy sheets.

6. The subject matter of claim 4 and said boxed in portion comprising an upstanding rectangular bottom plate at the rear end thereof, the upper edge of this plate engaging along the lower edge 10 portion of said arcuate plate and stabilizing the latter against bowing from the horizontal.

LOUIS G. HARLAM.
